Adolph W. Ewers, Chicago, Ill., assignor to
Arnold Brothers, Inc., Chicago, Ill., a corpora-
tion of Illinois

Application June 15, 1932, Serial No. 617,298

2 Claims. (Cl. 229—39)

The invention relates to improvements in boxes especially adapted to be made of paper or similar material, and has for its primary object the provision of an improved construction of this character by means of which a box of peculiar form and shape is produced.

Another object of the invention is the provision of a box of the character indicated having a top which may be arranged in either flat or gabled form.

Other objects will appear hereinafter.

The invention consists in the combinations and arrangements of parts hereinafter described and claimed.

The invention will be best understood by reference to the accompanying drawings forming a part of this specification, and in which

Fig. 1 is a perspective view of a box embodying the invention;

Fig. 2 a similar view showing the other side of the box;

Fig. 3 a bottom plan view of the box;

Fig. 4 an enlarged detailed section taken substantially on line 4—4 of Fig. 1;

Fig. 5 a plan view of the blank from which the box is made; and

Fig. 6 a perspective view of one end of the box shown as folded and arranged to provide a box having a flat top.

The embodiment of the invention illustrated in the drawings comprises a blank of paper, cardboard or the like, shaped as shown in Fig. 5, and containing opposite front and rear walls

11 and cooperating end walls 12. The rear wall 11 is provided with a securing flap 13 which is secured in the usual way by means of staples 14 to the front wall 12 to form a tubular folding box in the usual and well-known way.

The front, rear and end walls are provided with bottom flaps 15 and 16 which are folded and secured together as indicated in Fig. 3 to constitute the normal closed bottom of such a box. The details of the box already described are old and well-known for the purpose and constitute no part of the present invention except insofar as the same cooperate with the parts to be presently described.

The front wall 10 is provided with a cover flap 17 having a foldable locking flap 18 at its free edges, the side edges of the flap 18 being formed into rounded tongues 19 adapted and arranged to engage slits 20 in the opposite cover flap 21 at the top edge of the rear wall 11, as indicated in Fig. 6, whereby a box will be provided with a flat top. The cover member 21 is also provided at its free edge with a foldable locking flap 22 having the locking tongues 23 at its free edge adapted and arranged to engage and interlock with the slits 24 in the cover flap 17, as best indicated in Fig. 1, such arrangement serving as

shown to secure the cover members 17 and 21 in gabled form, as shown in Figs. 1, 2 and 4.

Each of the end walls 12 is provided at its top with a foldable triangular combined end and cover member 25 having a locking flap 26 along each free edge. By this arrangement, when the cover members 17 and 21 are arranged in gabled form, the members 25 are correspondingly arranged with the flaps 26 interlocking as shown in Fig. 2 with the tongues 19 and the slits 20, thereby holding the members 25 in upright position as indicated. When the cover members are folded flat, as indicated in Fig. 6, the triangular members 25 are also folded inwardly and flat within said cover members, as is usual in the ordinary flat top box.

By this arrangement a simple and effective box is provided which may be closed by a cover arranged in either gabled form, as indicated in Figs. 1 and 2, or in flat form, as indicated in Fig. 6. This will permit the use of the box for various purposes and for enclosing articles of various shapes, forms and sizes.

While I have illustrated and described the preferred form of construction for carrying my invention into effect, this is capable of variation and modification without departing from the spirit of the invention. I, therefore, do not wish to be limited to the precise details set forth, but desire to avail myself of such variations and modifications as fall within the scope of the appended claims.

I claim:

1. A box comprising bottom and side walls; rectangular cover member flaps at the tops of opposite walls, each of said cover member flaps being provided at its free end with a locking flap provided with tongues, there being slits in each of said cover flaps to engage the tongues on the other for securing said flaps in either flat or gabled form; triangular end flaps at the tops of the other opposite walls arranged to be either folded inwardly or to stand upright; and locking flaps at the free edges of said triangular flaps arranged to engage with the locking flap on one of said cover members to hold said triangular flaps upright.

2. A box comprising bottom and side walls; rectangular cover member flaps at the tops of opposite walls, each of said cover member flaps being provided at its free end with a locking flap provided with tongues, there being slits in each of said cover flaps to engage the tongues on the other for securing said flaps in either flat or gabled form; and triangular flaps at the tops of the other opposite walls arranged to be either folded inwardly or to stand upright and interfit with said rectangular flaps when in gabled form.
